UNITED STATES PATENT OFFICE.

HENRY C. TRAUTE, OF NEW YORK, N. Y.

DESIGN FOR A CASING FOR VENDING-MACHINES.

No. 37,605.

Specification for Design.

Patented Oct. 31, 1905.

Application filed August 25, 1905. Serial No. 275,845. Term of patent 14 years.

To all whom it may concern:

Be it known that I, HENRY C. TRAUTE, a citizen of the United States, residing at New York, in the county of New York and State of New York, have invented a new, original, and ornamental Design for a Casing for Vending-Machines, of which the following is a specification, reference being had to the accompanying drawing, forming part thereof.

The figure is a view in elevation of a vending-machine casing, showing my new design.

I claim—

The ornamental design for a casing for a vending-machine, as shown.

HENRY C. TRAUTE.
